CROWN CLOSURE LINING MACHINE

Dunbar L. Shanklin, Winchester, and Richard P. Stokes, Malden, Mass., assignors to Dewey and Almy Chemical Company, North Cambridge, Mass., a corporation of Massachusetts

Original application October 21, 1942, Serial No. 462,802. Divided and this application October 2, 1947, Serial No. 777,538

3 Claims. (Cl. 91—43)

1

This invention relates to a high speed, automatic machine for lining skirted closures and more particularly bottle crowns and caps according to the process claimed in the patent to Charles H. Egan, No. 1,956,012.

The function of the machine is to feed unlined crowns beneath nozzles which inject a liquid composition into the crowns, spin the crowns until the liquid composition has been banked against the vertical crown walls and then pass the crowns on to the belt of a drying apparatus where the liquid is evaporated from the composition and the composition is dried to form a distortable rubber-like seal which effectually closes a glass container in an hermetic manner.

The objects of the invention are to produce a machine capable of handling large numbers of crowns in a rapid and effective manner, perform the lining operations automatically, produce a machine which will not stop or be placed out of order if the sealing compound accidentally misses a crown and squirts into the machine parts, and produce a machine which will line crowns in a uniform manner to maintain close tolerances.

This application is a division of our co-pending application Serial Number 462,802, filed October 21, 1942 (now Patent No. 2,442,179, dated May 25, 1948), and the invention claimed herein relates especially to the arrangement for the simultaneous operation of the valves of a plurality of lining nozzles and the arrangement whereby one or more nozzles may be locked-out or prevented from operating at any time. Other constructions embodied in our machine are being claimed in co-pending applications Serial Numbers 539,659, filed June 10, 1944, now Patent No. 2,444,232, issued June 29, 1948, and 539,660, filed June 10, 1944.

The structure embodying the present invention is illustrated in the accompanying drawing in which

Figure 1 is a rear elevation of the crown lining machine, with the table top being shown in vertical section along the plane of the axes of the crown-rotating chucks;

Figure 2 is an enlarged fragmentary view in rear elevation, and partly in section, of the right end of Figure 1 showing the details of the valve operating arrangement for one of the lining nozzles; and Figure 3 is a plan view of Figure 2.

General organization

The machine for applying the lining compound comprises a table-like casting 30 having a base 31, side members 32 and a top or table 33. The

5 crowns are fed to the machine from a crown sorting and feeding mechanism of any conventional type. This mechanism serves to align the crowns with a series of feed chutes 34, and to pass into the chutes only crowns which face upwardly. The crowns slide down the chutes 34, by gravity, but are checked by an escapement mechanism and released one at a time to receivers 45 through which feed slides 35 reciprocate. Each of the receivers 45 comprises two parts which are secured to the table top 33, in properly spaced relation to provide a receiving chamber into which the crowns are discharged from the chute 34 and a channel through which the crowns are moved forward by the feed slide 35. The feed slides 35 move the crowns from the receiving chambers to rotary chucks 36. These chucks rotate the crowns while the compound is squirted into them from nozzles N. 10 When the crowns have been lined they are stripped from the chucks and moved forward through ways or tracks by stripper fingers to a group of distributing guides, by which they are placed on a conveyor belt and carried to the dryer. Since 15 the arrangements for feeding the crowns to the chucks and for removing lined crowns from the chucks form no part of the present invention, the details are not given here but are fully disclosed in our co-pending application 462,802, filed October 21, 1942, now Patent No. 2,442,179, issued May 25, 1948.

Chucks and chuck drive

The chucks 36 rotate continuously. Each chuck is provided in its upper face with a shallow counterbore 100 and communicating therewith is an axial bore 101. Each chuck is carried on a spindle 102 which is provided throughout its length with an axial bore 103 that is aligned with axial bore 101 and counterbore 100 of the chuck. Each spindle is mounted in ball bearings 104 which are fastened in the spindle beam 105. Each spindle 102 enters vacuum chest 106, through sleeve bearings 107. The chest 106 which acts as a spilled compound sump, is provided with cleanout plugs 25 and a removable cover. Rods 108 extending between the table top 30 and the chest 106 form guides on which the beam 105 is mounted and along which it reciprocates vertically. The vertical motion of the spindle beam 105 is derived from the cams 109 and 110 carried on shaft 112. Each cam works against a cam follower assembly which comprises a cam follower 113 carried by a spring biased arm 114 pivoted on the main frame at 115 and at

tached at 118 to the adjustable beam push rods 117. As shaft 112 revolves, the spindle beam 105, and, consequently, all of the chucks 36, will rise and fall. Each spindle bears a vertically movable gear 120 which meshes with fixed gears 121. The gears 120 are driven by a gear 122 meshing with at least one of the gears 121 and carried on the shaft 123 which is journaled in a special extension 124 of the vacuum chest 106. The lower end of shaft 123 bears a bevel pinion 125, which meshes with the bevel gear 126 carried on the shaft 70. The shaft 70 is driven by gears 22 from the shaft 112 which is itself driven by a motor through a chain 23 and a sprocket carried by shaft 112.

The vertical motion of the chucks 36 is in timed relation to the movement of the feed slides 35. The chucks remain down throughout most of the forward strokes of the feed slides. Upon advance of the feed slides, the stripper fingers pass above the chucks 36 and sweep the lined crowns off and into the ways, while the feed slides 35 push the next crowns through the channels and onto the chuck faces.

The crowns are pushed nearly to their final positions on the chucks by the feed slides. They are guided into final position by the vertical walls of the counterbores 100. Each crown is seated on the circular edge formed at the junction of the counterbore 100 and the axial bore 101, and when seated, shuts off the flow of air into the chuck.

The nozzles N differ but slightly from nozzles used on can end lining machines. Each consists of a stainless steel body 130 having a replaceable nose piece 131, a needle 132 and a spring barrel 133. A spring 134 bears against a collar supported by a shoulder on the needle and normally urges the needle against a ground seat in the nose piece. Lining compound is prevented from entering the spring housing by the diaphragm 135. The immediate supply of lining compound is stored in a tank 136 and delivered through a tube 20, to the manifold 137 and from the manifold through tubes 17 to the nozzles N by a pneumatic head of a few pounds derived from the compressor 138. Manifold 137 is supported by brackets 18 secured to a cross rail 19 which is itself adjustably supported by brackets 159 and 160 secured to opposite sides of the table 30. When the needle 132 is raised in the nozzle N, a stream of compound is shot downwardly. With the pneumatic head and diameter of the orifice in the nose piece 131 fixed, the quantity of compound which the nozzle delivers is controlled by the lift of the needle. Adjustment of needle lift is secured by means of handwheels 140, 141 which are in threaded engagement with needle pull rods 142, the upper handwheels 141 serving merely as lock nuts, while the lower handwheels 140 make the actual adjustment.

Individual lock-out

A slide rod 143 on the needle lift bar 144 which is slidably mounted in lift bar 144 beneath cover plates 144' operates a number of latches 145. Latches 145 are provided with apertures 146 through which the needle pull rods 142 pass. The apertures 146 are keyhole shaped so that they clear the needle pull rods 142 but engage the bottom face e of the needle adjusting handwheels 140 when the latches 145 are in their operating positions shown most clearly in Figures 2 and 3. Each of the latches 145 is provided with an upstanding handle 147 which is received between

the arms of a fork 148 secured to the slide rod 143. Handles 147 carry spring pressed balls 149 which are adapted to engage either one of two notches g formed in a portion of the needle lift bar 144. The notches g are spaced to limit the movement of the latch to its operative and inoperative positions. When either handle 150 of the slide rod 143 is moved toward the right, the enlarged portions of the apertures 146 of the latches 145 then clear the shank portions f of the adjusting handwheels 140 and all of the needles are then rendered inoperative. However, any one of the latches may be actuated independently to render its corresponding needle operative or inoperative by manipulation of one of the handles 147. For example, in Figure 1, the handle 147' is shown in position to render the latch 145' inoperative while the remainder of the latches are in their operative positions. It will be understood that the shank portions f of the handwheels 140 constitute adjustable abutments carried by the rods 142 and these abutments seat upon the latches 145 in one position of the latches so that the rods 142 are reciprocated with the lift bar 144.

The vertical movement of the needle lift bar 144 is secured by motion derived from cams 155 and 156 mounted on the opposite outboard ends of the shaft 112. The cam motion is transmitted through cam followers 9 and 10, and connecting rods 12 and 13 to the beam push rods 157 and 158 which are guided for vertical movement in sleeves carried by the brackets 159 and 160 previously referred to. Springs, surrounding the push rods and mounted between the table 30 and a collar 14 on the rods, urge the cam followers 9 and 10 into continuous contact with their respective cams. When the shaft 112 revolves, the needle beam 144 is raised and lowered in timed relation to the other operations of the machine.

As previously explained, the crowns, when seated on the chucks 36, form an effectual seal which prevents the passage of air through the chucks 36 and the chuck spindles 102. By connecting a vacuum pump with the vacuum chest 106 by means of a tube 165 a continuous current of air is pulled through the chucks. Thus when a crown is moved onto the face of a chuck it is pulled into position in the counterbore by the vacuum which is created.

The needles 132 and chucks 36 lift practically at the same moment and just before the chuck and the crown which it holds, reaches its top position, the compound flows into the crown. Then the needle lift bar 144 falls, the nozzles close and the flow of compound to all crowns stops before the chucks begin to descend. The loaded crowns spin in the raised position after the flow of compound stops. The rotary speed of the chuck is set to create a centrifugal force greater than the yield value of the lining composition so that the compound squirted into the center of the crown is banked against its vertical walls. The cross section of a lined crown (Figure 2) shows the type of lining which is secured by this operation. The entire inner surface of the crown is covered with compound which is materially thinner in the center, or non-sealing portion, and thicker at the edges where a mass of sealing material is required to form a plastic seat for the open end of a bottle or other container.

After the lining has been formed as described, the chuck falls, the feed slides 35 and stripper fingers begin to advance and the machine begins a second cycle of operation.

Although the machine has been described as

"a crown lining machine," and crowns of the familiar type have been illustrated, it is obvious that the machine is equally well adapted to the lining of skirted container closures of any type and we intend that the word "crown" as used in the specification and claims shall include skirted closures generally.

We claim:

1. In a machine for lining closures, the combination of a plurality of rotary chucks, a lining compound applying nozzle associated with each chuck and having a needle movable therein to open or close its outlet, a horizontal lift bar mounted for vertical reciprocation, operating rods extending from the needles through the lift bar and slidably therethrough, an abutment on each rod on the opposite side of the bar from the needle, and latch members on the bar individually movable into or out of position for the seating of said abutments upon said latch members, whereby said rods are reciprocated by said lift bar.

2. In a machine for lining closures, the combination of a plurality of rotary chucks, a lining compound applying nozzle associated with each chuck, and having a needle movable therein to open or close its outlet, a horizontal lift bar mounted for vertical reciprocation, operating rods extending from the needles through the lift bar and slidably therethrough, an abutment on each rod on the opposite side of the bar from the needle, latch members on the bar individ-

ually movable into or out of position for the seating of said abutments upon said latch members, whereby said rods are reciprocated by said lift bar, and means for simultaneously moving all of the latch members into or out of seating position.

3. In a machine for lining closures, the combination of a plurality of rotary chucks, a lining compound applying nozzle associated with each chuck and having a needle movable therein to open or close its outlet, an operating member common to all of the said needles, means mounting said operating member adjacent said needles for reciprocation in a direction parallel to the axes of said needles, and individually latched members carried by said operating member and connecting said needles to said reciprocating member for reciprocation therewith, said latch members being individually movable out of latching position whereby any desired needle may be disconnected from said reciprocating member.
